Primary Examiner — Eric Goodman*Assistant Examiner* — Clese Moore, Jr.(74) *Attorney, Agent, or Firm* — Leanne Taveggia Farrell; Westman, Champlin & Koehler, P.A.(57) **CLAIM**

The ornamental design for a display fixture, as shown and described.

DESCRIPTION

FIG. 1 is a perspective view of a first embodiment of a display fixture showing our new design;

FIG. 2 is a side view thereof, the opposing side view being identical;

FIG. 3 is a front view thereof, the back view being identical;

FIG. 4 is a top view thereof;

FIG. 5 is an enlarged section view representative of the sections indicated by the lines in FIG. 4 and is shown without the rest of the claimed display fixture for convenience of illustration; and,

FIG. 6 is an enlarged section view representative of the sections indicated by the lines in FIG. 4 and is shown without the rest of the claimed display fixture for convenience of illustration.

The broken lines illustrate portions of the display fixture and form no part of the claimed design.
